MOUNTING PLATE FOR A PNEUMATIC VEHICLE IMPACT BUMPER

Wilbur L. Hiatt, 4508 Commonwealth Drive, Williamsburg Apt. N., Indianapolis, Ind. 46220

Filed May 6, 1971, Ser. No. 141,076

Term of patent 14 years

Int. Cl. D12—16

U.S. Cl. D14—6

FIG. 1 is a rear elevation of a mounting plate for a pneumatic vehicle impact bumper of the present invention with the length of the plate extending vertically.

FIG. 2 is a top plan view of the structure of FIG. 1.

FIG. 3 is a front elevation of the mounting plate of FIGS. 1 and 2.

FIG. 4 is an enlarged end elevation of the structure illustrated in FIGS. 1, 2, and 3.

FIG. 5 is an enlarged section taken along the line 5—5 of FIG. 1 in the direction of the arrows.

The bottom plan view of the structure is identical to FIG. 2.

The end of the structure opposite to the end illustrated in FIG. 4 is identical to the end illustrated in FIG. 4.

I claim:

The ornamental design for a mounting plate for a pneumatic vehicle impact bumper, as shown and described.
